UNITED STATES PATENT OFFICE.

JAMES PECKOVER, OF PHILADELPHIA, PENNSYLVANIA.

RECIPROCATING MACHINE.

SPECIFICATION forming part of Letters Patent No. 690,316, dated December 31, 1901.

Application filed July 18, 1900. Serial No. 24,012. (No model.)

To all whom it may concern:

Be it known that I, JAMES PECKOVER, residing at Philadelphia, State of Pennsylvania, have invented new and useful Improvements 5 in Stone-Sawing Machines, of which the following is a specification.

My invention relates to certain improvements in stone-sawing mechanism, and more particularly to improvements in the construction 10 and arrangement of the detail parts thereof.

One object of my invention is to provide means whereby a machine of the type described may more quickly and efficiently perform its work, a further object being to provide protection for the parts liable to injury from the action of grit or other foreign substances. These objects I attain as herein-after set forth, reference being had to the accompanying drawings, in which—

Figure 1 is a plan view of sufficient of a stone-sawing machine, illustrating my invention. Fig. 2 is a longitudinal sectional view of the same, taken on the line 2 2, Fig. 1. Fig. 25 3 is a transverse sectional view on the line 3 3, Fig. 1. Fig. 4 is an enlarged longitudinal sectional view of part of the carrier-frame. Fig. 5 is an enlarged transverse sectional view of the same, and Fig 6 is a view of a modification 30 of the device for slightly raising the saw-frame at the end of each stroke.

In the drawings, A A are the posts or main supports of the main frame of a machine to which my invention is applied, having secured to them vertical screws a a, which are journaled and operated to raise or lower the sawing mechanism in any of the various ways known to the art. Threaded on these screws are nuts a' a', each with a pivot projecting 35 from it, to which are hung the pendent rods a² a². Connected to these rods is a carrier-frame consisting of elongated box-like side members B and end members B', these latter being rods or bars on which are distance-nuts b' b' and retaining-nuts b² b². As will be seen 40 from Figs. 3 and 5, the side members B are preferably made of two channel-irons b b, placed with their flanges facing and held together by a plate b³, extending over their tops. 45 The rods a² pass through this plate and are each provided with a nut and washer-plate, as shown. Plates b³ are placed over the ends of

these box-like side members B. Pieces b⁴, held to the channel-irons by bolts b⁵, have attached to them the slides or bearing-surfaces b⁶, in which are recesses holding glass disks b⁷. These latter are convex on their upper sides and flat on their lower surfaces and are embedded in Babbitt metal to the level of their top surfaces.

Rollers c c, for a purpose set forth herein-after, are fitted to bearings in the pieces b⁴, and they also serve as distance-pieces to prevent any tendency of the channel-irons b b to close the slot between their lower flanges.

A saw-frame is hung from the above-described carrier-frame by four runners d d, which are preferably made of sections of I-beams with the under faces of their upper flanges finished to run smoothly on the slides b⁶, the said slides being sloped to accommodate the inclination of the runner-flanges. The saw-frame itself consists of end members D D, each consisting of a pair of channels bolted together back to back, preferably with a plate between them, the two members being joined by the saws d¹ d¹, of which there are two in the present instance, these being bolted to the end members of the frame and operating in the kerfs d³ d³ of a stone, as shown. Recesses d² are cut in the ends of the web of each runner d, and the square upper corner of each recess is cut off diagonally, as plainly shown in Fig. 4.

E is a pedestal having across its upper part a bar e, to which is pivoted one end of the rods e' e', their other ends being connected to the carrier-frame by its end members B'. The pedestal also has bearings in it for the support of the driving-shaft e², the latter being connected to any suitable source of power. There is a crank e³ on this shaft, and a connecting-rod e⁴ extends between it and the end of the saw-frame.

In operation as the shaft e² is rotated the revolution of the crank reciprocates the saw-frame, running the saws through the kerfs. By means of mechanism (not shown) attached to the screws a a, the carrier-frame is held at such a height by the pendent rods a² and the nuts a' that during the greater part of the stroke most of the weight of the end members D is taken by the saws, their cutting edges being pressed against the floor of the

kerfs. Near the end of each stroke the runners come in contact with one set of rollers *c c* and the continued motion of the connecting-rod compelling the saw-frame to move 5 farther toward said rollers, the diagonally cut edge and then the straight edge of the recess *d²* in the webs of the runners, rides up on the same. This bodily lifts the saw-frame and with it the saws, the whole being 10 held in this position until the connecting-rod begins to move in the opposite direction, when the runners slide off the rollers and drop the saws quite heavily upon the bottom or floor of the kerfs, the whole operation being 15 similarly repeated at the other end of the stroke. When the saw-frame is lifted at the end of each stroke, the water and abrading material is allowed to get underneath the saw-blades, and these latter are permitted to regain 20 their normal shape, it being generally the case that they warp during the stroke. By thus avoiding this objectionable warping of the saws the stone is cut by much straighter kerfs than would otherwise be formed and consider- 25 able expense is saved, since comparatively little working over of the slabs is required when the cutting is finished. Again, when the saws are dropped into the kerfs as the runners slide off the rollers at the beginning of 30 each stroke the abrading material which has run under the saws while they were elevated is pounded into the stone, thus materially hur- 35 rying its disintegration in the line cut and materially aiding the sawing thereof.

35 It will be understood that I do not confine myself solely to the use of rollers for lifting the saw-frame, as, if desired, I may use an ob- 40 stacle of the form shown at *e³*, Fig. 6.

It has been found that glass, by combining 40 both smoothness and hardness, makes a very valuable antifriction material for the runners to slide on, the only objection being that its brittleness renders it extremely liable to destruction. This bad feature has been over- 45 come by embedding the glass in the shape of convex disks in Babbitt metal in recesses in the slides, a method of construction which has been found to effectually protect it.

It will be noticed that by inclosing the 50 slides with the bearing-surfaces of the runners in a tight box-like structure, the grit and other foreign injurious matter is kept off of these very delicate parts of the machine, their life being greatly prolonged thereby 55 and the cost of maintenance correspondingly reduced.

In order that as the depth of the saw cuts 60 or kerfs increases the saw-frame and carrier-frame may retain the same position relatively to one another, the bar *e'*, by which the said carrier-frame is anchored, is made the same length as the connecting-rod. By this means 65 the pivotal points of the two frames or the points at which they are connected to the rods *e'* and *e⁴*, respectively, are made to describe similar arcs around the points of revolution *e* and *e²* as the saw cuts through the

stone, and are consequently made to operate in the most advantageous manner.

I claim as my invention—

1. The combination in a stone-cutting ma- 70 chine, of a supporting-frame, a carrier-frame supported thereon, slides inclosed on all sides within said carrier-frame, and a saw-frame having runners projecting through an opening 75 in the lower face of the carrier-frame constructed to operate on said slides, with means for reciprocating the saw-frame, substantially as described.

2. The combination in a stone-cutting ma- 80 chine, of a main frame, a carrier-frame hung therefrom, said carrier-frame having side members composed of slides inclosed in an elongated box-like structure, a saw-frame 85 having runners constructed to operate on said inclosed slides, the runners entering said inclosed structure through relatively narrow slots in the carrier-frame, with means for reciprocating the saw-frame, substantially as described.

3. In a stone-sawing machine, the combination of a main frame, a carrier-frame hung therefrom having box-like side members, a saw-frame with saws constructed to be reciprocated while being supported from the carrier-frame, slides within the side members of the carrier-frame and runners on the saw-frame entering slots in the bottom faces of the side members on the carrier-frame and bearing upon the said slides, with means on the carrier-frame for lifting the saw-frame at the end of each stroke and means for reciprocating the saw-frame, substantially as described.

4. The combination in a stone-sawing ma- 105 chine, of a main frame, a carrier-frame hung therefrom, said carrier-frame consisting of two hollow elongated side members having slides therein, and a slot opening into them, said members being held together by two end 110 members, a saw-frame having runners projecting through the slots in the side members of the carrier-frame, and constructed to operate on the slides, with means independent of the slides for raising and afterward dropping 115 the saw-frame as it nears the end of each stroke, substantially as described.

5. The combination in a stone-cutting ma- 120 chine, of a main frame, a carrier-frame hung therefrom and having inclosed slides, a relatively narrow slot in said carrier-frame opening into the inclosed slides, pieces in the slot extending from side to side thereof, a saw-frame having runners entering the slot and operating on said slides, means for reciprocating the saw-frame, said runners with said frame being constructed to be raised when brought into engagement with said pieces in the slots, substantially as described.

6. The combination in a stone-cutting ma- 130 chine, of a main frame, a carrier-frame hung therefrom constructed with inclosed slides, a relatively narrow slot in said carrier-frame opening into said slides, rollers supported in

5 said slot with their axes of revolution at right angles to the length of the slots, a saw-frame having runners entering the slot and operating on the slides, means for reciprocating the saw-frame, the runners with their attached frame being constructed to be raised when brought into engagement with the said rollers, substantially as described.

7. In a stone-sawing machine, the combination of a main frame, a carrier-frame hung therefrom, slides on said carrier-frame, a saw-frame having runners, each of said runners consisting of a head-section connected to the saw-frame by a web-section, the under side 10 of said head-section bearing on said slides, with means for reciprocating the saw-frame, substantially as described.

8. In a stone-cutting machine, the combination of a main frame, a carrier-frame hung

therefrom, said carrier-frame having inclosed 20 within it slides with a relatively narrow slot opening into them, rollers in the slot, a saw-frame having runners entering the said slots, means for reciprocating said frame, said runners being constructed to operate on the 25 slides, each having in it a recess, the edge of which is constructed to engage the roller and thereby alternately raise and lower the saw-frame at certain points of its stroke as the machine operates, substantially as described. 30

In testimony whereof I have signed my name to this specification in the presence of two subscribing witnesses.

JAMES PECKOVER.
